UNITED STATES PATENT OFFICE.

EMIL NASTRI, OF BROOKLYN, NEW YORK.

WINDOW SEAT.

Application filed February 10, 1926. Serial No. 87,424.

To all whom it may concern:

Be it known that I, EMIL NASTRI, a citizen of the United States, residing at Brooklyn, in the county of Kings, State of New York, 5 have invented certain new and useful Improvements in Window Seats; and I do hereby declare the following to be a full, clear, and exact description of the invention, such as will enable others skilled in the art to 10 which it appertains to make and use the same.

This invention relates to new and useful improvements in seats, and particularly to seats adapted to be attached to window sills 15 to support persons cleaning windows.

One object of the invention is to provide a device of this character which is simple in construction, and which can be manufactured at a low cost.

20 Another object is to provide a device of this character which is strong and durable, and which can be easily and quickly, as well as securely attached to a window sill.

Other objects and advantages will be apparent from the following description when 25 taken in connection with the accompanying drawing.

In the drawing:

Figure 1 is a side elevation of a window 30 seat, made in accordance with the present invention.

Figure 2 is a top plan view of the same.

Figure 3 is a transverse sectional view on the line 3—3 of Figure 1.

35 Referring particularly to the accompanying drawing, 10 represents the substantially U-shaped frame of a clamp, which is provided with the clamping screw 11 in one leg thereof for biting engagement with one

side of a window sill, while the other leg is 40 provided with a foot 12, for engagement with the opposite side of the sill. Carried by the lower face of the bight portion of the frame 10 is a downwardly extending bifurcated member 13, the legs of which are 45 directed laterally from the frame 10, for engagement on the upper face of the sill, to maintain the frame from lateral rocking movement, on the sill. A substantially V-shaped member has the ends of its legs 14 and 15, secured to the sill engaging leg of the frame 10, intermediate the length thereof, and the frame, above the member 13, respectively, said V-shaped member extending outwardly from the outer end of the 55 frame. Secured on the upper leg 15, of the member 14—15, is the seat 16, having the back rest 17 secured thereon.

From the foregoing it will be seen that I have provided a simple and durable seat 60 which is adapted to be securely clamped to a window sill, so that the seat will be disposed outwardly of the window, and properly and safely support the person who is 65 to clean the window.

What is claimed is:

A window seat including a U-shaped screw clamp, a V-shaped member having its legs secured to one end of the clamp and extending away therefrom, a seat carried by the 70 outer end of one of the said legs, and a bifurcated downwardly flaring member carried by the intermediate portion of the clamp for engagement with a window sill whereby to prevent sidewise rocking movement of 75 the clamp.

In testimony whereof, I affix my signature.
EMIL NASTRI.
